Primary Examiner — Deanna L Pratt*(74) Attorney, Agent, or Firm* — Alan D. Kamrath; Karin L. Williams; Mayer & Williams PC(57) **CLAIM**

The ornamental design for a latch for snips, as shown and described.

DESCRIPTION

FIG. 1 is a perspective view of a latch for snips showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a partial cross-sectional view of the latch for snips showing my new design, and shows how the latch for snips applied to a snip.
